(57) **CLAIM**

The ornamental design for a solar charging organizer, as shown and described.

DESCRIPTION

FIG. 1 is a front perspective view of a solar charging organizer showing our new design including a shoulder strap, wherein the solar charging organizer is in a closed configuration;

FIG. 2 is a rear perspective view thereof, including a shoulder strap, wherein the solar charging organizer is in a closed configuration;

FIG. 3 is a front perspective view thereof, without a shoulder strap, wherein the solar charging organizer is in an open configuration;

FIG. 4 is a rear perspective view thereof, without a shoulder strap, wherein the solar charging organizer is in an open configuration;

FIG. 5 is a front plan view thereof, without a shoulder strap, wherein the solar charging organizer is in an open configuration;

FIG. 6 is a rear plan view thereof, without a shoulder strap, wherein the solar charging organizer is in an open configuration;

FIG. 7 is a top plan thereof, without a shoulder strap, wherein the solar charging organizer is in an open configuration;

FIG. 8 is a right plan view thereof, without a shoulder strap, wherein the solar charging organizer is in an open configuration;

FIG. 9 is a front perspective view thereof, with a shoulder strap, wherein the solar charging organizer is in an open configuration; and,

FIG. 10 is a front elevation view thereof, with a shoulder strap, wherein the solar charging organizer is in an open configuration.

The strap is shown removed from the bag for convenience of illustration only.

The broken lines illustrate stitching and form no part of the claimed design.

1 Claim, 9 Drawing Sheets
